UNITED STATES PATENT OFFICE

WILLIAM H. RICHARDSON, OF MOBILE, ALABAMA.

IMPROVEMENT IN SWIMMING-MACHINES.

Specification forming part of Letters Patent No. 222,951, dated December 23, 1879; application filed September 10, 1879.

To all whom it may concern:

Be it known that I, WILLIAM HALL RICHARDSON, of Mobile, in the county of Mobile and State of Alabama, have invented a new and useful Improvement in Swimming-Machines, of which the following is a specification.

Figure 1 is a side elevation of my improved swimming-machine. Fig. 2 is a plan view of the same. Fig. 3 is a detail view of the lower portion of the same.

The object of this invention is to furnish a float provided with a propelling mechanism, the use of which will allow a swimmer to make his way rapidly and safely through the water.

The invention consists in combining with a float a propeller operated by hand mechanism at one end and foot mechanism at the other, as hereinafter described.

Similar letters of reference indicate corresponding parts.

A represents a float of sufficient buoyancy to sustain the mechanism and the swimmer. The float A is attached to two rods, B, at a little distance from their forward ends. The forward ends of the rods B are attached to the middle part of a U-bar, C, near its angles. The rear ends of the rods B are attached to a bearing-block, D. In the ends of the bar C revolves a shaft, E, which has cranks F formed upon or attached to its ends. To the shaft E is attached a large bevel-gear wheel, G, the teeth of which mesh into the teeth of a small bevel-gear wheel, H, attached to the forward end of a shaft, I. The shaft I revolves in bearings in the center of the bar C in the float A and in the bearing-block D. In the block

D revolves a shaft, J, which has cranks K attached to or formed upon its ends. The cranks K have foot-rests L pivoted to them to receive the feet of the swimmer, and provided with straps for securing his feet in place.

To the shaft J is attached a large bevel-gear wheel, M, the teeth of which mesh into the teeth of a small bevel-gear wheel, N, attached to the shaft I. The large gear-wheels G M are arranged upon the opposite sides of the shaft I, so as to balance each other. To the rear end of the shaft I is attached a propeller, O, the wings of which are made light, and have a ring attached to their outer ends to strengthen and protect them.

In using the machine the swimmer places his chest upon the float A, places his feet upon the foot-rests L, and grasps the cranks F with his hands, so that he may apply power to the propeller O with his hands and feet, or with either hands or feet. In using the machine it should be held in an inclined position, with its forward end above and its rear end below the surface of the water.

Having thus fully described my invention, I claim as new and desire to secure by Letters Patent—

The combination of the float A, rods B, U-bar C, having hand crank-shaft E, block D, having foot crank-shaft J, and the shaft I, carrying propeller O, said shafts being connected by bevel-gears, as shown and described.

WILLIAM HALL RICHARDSON.
